UNITED STATES PATENT OFFICE

2,473,057

BUTTER DISPENSING MACHINE

Leonard Herber, Minneapolis, Minn.

Application February 25, 1946, Serial No. 649,964

12 Claims. (Cl. 31—20)

1

This invention relates to a butter-cutting and dispensing machine. It is now desirable in many restaurants, hotels and other places to have a machine which will cut and dispense small pieces or pats of butter which are to be served to the patrons. Such a machine should be constructed to contain considerable butter, keep the same in firm and solid condition and rapidly cut and dispense the same.

It is an object of this invention to provide a simple, compact and easily operated machine for containing blocks of butter and for cutting and dispensing small pieces or pats of butter.

It is also an object of the invention to provide such a machine as set forth in the preceding paragraph which comprises an outer casing having an insulated wall, an inner casing spaced from said wall to form a chamber adapted to contain refrigerant and a butter-carrying member having butter-receiving chambers movable closely adjacent the wall of said inner casing.

It is another object of the invention to provide a butter-cutting and dispensing machine comprising a casing, a member rotatable about a central longitudinal axis and carrying a plurality of radially disposed and circumferentially spaced chambers each substantially rectangular in cross section and adapted to receive and guide a block of butter, said casing having an opening with doors closing the same whereby when said doors are open several of said chambers have their open ends exposed so that butter can be loaded thereto.

It is a further object of the invention to provide a butter-cutting and dispensing device comprising a member rotatable about a central longitudinal axis and carrying a plurality of radially disposed and circumferentially spaced chambers each substantially rectangular in cross section and having an open side, the same being constructed and arranged to receive and guide an elongated block of butter, an endless member having a rectilinear side extending substantially parallel to said chambers adjacent which said chambers are successively positioned by rotation of said first mentioned member, butter-propelling members carried by said endless member adapted to extend through the open side of the chamber adjacent said endless member and to move into one end thereof through and out of the other end thereof, said endless member being movable only in one direction, a butter-cutting member, a handle at the exterior of said device, and means operated by movement of said handle for actuating said cutting means to cut

2

a slice of butter from the block and the chamber adjacent said endless member and then to advance said endless member and butter-propelling members a distance equal to the thickness of said slice.

It is more specifically an object of the invention to provide a butter-cutting and dispensing device comprising a casing having a refrigerated space therein, a member in said space rotatable about a central longitudinal axis and carrying a plurality of radially disposed and circumferentially spaced chambers each substantially rectangular in cross section having an open side and adapted to receive and guide an elongated block of butter, a pair of sprockets, a chain running over said sprockets having a side extending therebetween and substantially parallel to said chambers, said chambers being successively positioned adjacent said side of said chain by rotation of said member, butter-propelling members carried by said chain and adapted to extend through the open side of the chamber adjacent said chain, to move into one end of said chamber, pass therethrough and move out of the other end, said chain being movable only in one direction, a swinging frame pivoted at one side of said first mentioned member and carrying a rectilinear wire, a ratchet wheel connected to one of said sprockets, a handle at the outer side of said device, and means operable by said handle for swinging said frame to move said wire across the end of the chamber adjacent said chain to cut a pat of butter from the block therein and then to operate said ratchet to move said chain a distance equal to the thickness of said slice.

These and other objects and advantages of the invention will be fully set forth in the following description made in connection with the accompanying drawings in which like reference characters refer to similar parts throughout the several views and in which:

Fig. 1 is a view in front elevation of the device, a small portion being broken away;

Fig. 2 is a vertical section taken substantially on line 2—2 of Fig. 4, as indicated by the arrows;

Fig. 3 is a partial vertical section taken substantially on line 3—3 of Fig. 2, as indicated by the arrows;

Fig. 4 is a horizontal section taken substantially on line 4—4 of Fig. 1, as indicated by the arrows; and

Fig. 5 is a partial vertical section taken substantially on line 5—5 of Fig. 3, as indicated by the arrows.

Referring to the drawings, a device is shown

comprising an outer casing 10. While casing 10 might take various forms, in the embodiment of the invention illustrated, it is shown as substantially rectangular in horizontal and vertical cross section having vertical side walls 10a, a top wall or cover 10b, and a bottom wall 10c. Said walls comprise spaced plates between which some good heat insulating material 11, such as cork, is placed. A flange 10d, substantially rectangular in horizontal cross section, extends downwardly from the sides of casing 10 below the lower wall 10c to form a supporting means, and said flange is cut away at the central portions of the sides thereof to form corner legs 10e. The top wall 10b may be in the form of a removable lid or cover, the same having a flange 10f extending downwardly thereabout adapted to fit around the sides 10a and having an inner flange 10g adapted to rest on the top of the side walls 10a. Cover 10b is preferably provided with a handle 10j which can conveniently be connected to the top plate of cover 10b by screws 12 engaging washers 12a. One side wall 10a is provided with an opening preferably rectangular in shape extending to bottom wall 10c in which a door 13 tightly fits, the same having a flange 13a over-lapping the side wall about said opening. Door 13 will preferably be provided with a suitable handle 14. Handle 14 is shown as having threaded studs extending through the wall of door 13, the same being provided with nuts 15 overlying washers 16 engaging the inner side of door 13. Casing 10 also has an opening 10k at one side adjacent its top which may be called the front side, which opening is closed by a pair of doors 18 swingable on hinges 19 at their remote sides so that they open away from each other. Doors 18 meet at their free edges when in closed position and are provided with suitable handles 18a. An inner casing 21 is provided having an outer wall 21a extending along the inner side of rear wall 10a and along opposite side walls 10a, as shown in Fig. 4. Casing 21 has an inner wall 21b which at its lower portions extends parallel to the outer wall 21a but which is semi-cylindrical at its central portion, as shown in Fig. 2. A chamber is thus formed within the inner wall 21b which is open at its bottom. Casing 21 has a bottom portion 21c at one end which slopes downwardly toward one side of casing 10 and casing 21 at said side is provided with drain spouts and openings 21d. Casing 21 is supported upon angle members 22 and 23 secured in any suitable manner as by welding to the inner plates of side walls 10a. A receptacle 25, illustrated as rectangular in horizontal and vertical cross section, has a flanged bottom resting on bottom plate 10c and the same has its open upper end disposed beneath the spouts and openings 21d. Receptacle 25 is of such size that it can be readily removed through the opening closed by door 13. The inner wall 21b of casing 21 extends upwardly above the tops of the side walls 10a, the same having a shoulder extending a slight distance over said tops and the upper edge of said wall is disposed so as to be substantially engaged by the bottom of cover 10b.

A bracket 28 is provided having a bottom flange resting on bottom wall 10c and secured thereto by headed bolts 29. Bracket 28 has at one end a bearing 28a in which one end of a shaft 30 is journaled, the other end of said shaft being journaled in a bearing 31 extending through front wall 10a and having a flange engaging the outer side of said wall and secured thereto by headed screws 32. Shaft 30 has secured thereto a mem-

ber 34. Member 34 comprises end members 34a having peripheral flanges of octagonal shape, as shown in Fig. 2, and as having end flanges at their remote ends. One end member 34a has a central hub 34b connected to its end flange which is in turn secured to shaft 30. The other end member 34a is engaged at its outer side by the flange 35a of a member 35 having a hub the end of which engages the inner side of bearing 28a and which hub is secured to shaft 30 in any suitable manner, as by a set screw 36. Secured to the outer sides of the peripheral flanges of members 34a in any suitable manner, as by welding, are a plurality of casings or chambers 38. Members 38 are shown as formed of sheet material or metal and each is substantially rectangular in cross section and provided with an open side 38a. Each member 38 has a small plate or disk 39 secured to its outer side, which disk has an opening there-in adapted to receive the end of a pin 40 which is carried in and longitudinally movable in a casing 41 extending through one wall 10a and having an outer flange 41a secured to said wall by headed and nutted bolts 42 having their heads countersunk in said flange. Casing 41 has a cylindrical chamber therein and pin 40 has a collar 40a substantially fitting in said chamber and engaged at one end by compression coiled spring 43 which surrounds pin 40 and engages at its other end the end of casing 43. Pin 40 at its outer end is provided with a knurled knob or handle 44. Members 38 are shown as braced and connected by gusset plates 45. A handle 47 is connected to the end of shaft 30 at the front side of casing 10, the same engaging the outer end of bearing 31 and being secured to shaft 30 in any suitable manner, as by a pin 48. Handle 47 is in the form of a crank having a handle portion 47a. It will be seen that rotation of handle 47 and shaft 30 will rotate member 34 and members 38 carried thereon.

Bracket 28 has a bearing 28b in which is journaled a shaft 50 to which is secured a sprocket 51. A bracket 49 is secured to bottom 10c by bolts 49a having a bearing 49b in which is journaled a shaft 52 having secured thereto a sprocket 53 aligned with sprocket 51. An endless chain 54 runs over sprockets 51 and 53 and the same has secured thereto butter-propelling means or plates 55. Plates 55 are shaped as shown in Fig. 5, the same having laterally extending portions adapted to pass through the opening 38a in the side of the member 38 which is disposed adjacent chain 54. It will be seen that members 38 can successively be brought into the lowermost position of member 34, in which position they are adjacent chain 54 and extend substantially parallel to one side thereof. Shaft 52 at its other end has secured thereto a helical gear 57 with which meshes a helical gear 58 secured to a shaft 60 journaled in bearings 49c of bracket 49. Shaft 60 also has secured thereto a ratchet wheel 61. A pawl 62 has its pointed end disposed in engagement with ratchet wheel 61 and is pivotally carried at the end of an arm 63 journaled on a shaft 64 journaled in bearings 66a of a bracket 66 secured to bottom wall 10c by headed screws 61. Pawl 62 is connected to arm 63 by a pivot pin 68. A plate spring 59 engages pawl 62 to hold it in contact with pawl 62. Secured to shaft 64 is a frame 70 comprising a top bar 70a having downwardly extending portions between which extends a taut fine wire 71. Frame 70 comprises a plate 70b moving adjacent arm 63 and having an arcuate slot 70c therein concentric with shaft 64 in which

extends a pin 72 secured to arm 63. The movement of arm 63 is limited by a headed screw 74 secured in wall 10a and provided with a lock or jamb nut 75. Screw 74 is adapted to engage the lower end of arm 63. Arm 63 has an upwardly extending projection 63a adapted to engage the end of a screw 76 secured in the wall 10a and provided with a lock or jamb nut 77. Screws 74 and 76 can be suitably adjusted to the desired position. A handle 78 is secured to one end of shaft 60 at the front side of casing 10 in any suitable manner, as by a pin 79. Handle 78 is in the form of a crank and is provided with a handle 78a. A tensile coiled spring 82 has one end secured to bar 70a and its other end upper end secured to a lug on a plate 83 secured to the inner side of wall 10a in any suitable manner, as by welding. The bottom wall 10c is provided with an opening 10m into which fits a guide or funnel 84 having its upper end disposed below the end of the lowermost member 38. Guide brackets 85 are secured to the bottom of wall 10c at each side of the opening 10m having flanges spaced from said wall and in which slides a plate-like member 86. Member 86 can be moved to positions either to close or open the opening 10m.

In operation a quantity of ice 98 will be placed in the chamber formed between casings 10 and 21. This ice can be conveniently placed in the device by removing the cover 10b. Doors 18 will be opened and blocks of butter such as the standard one-fourth pound blocks will be placed in the chambers 38. It will be seen from Fig. 1 that when doors 18 are open three of the members 38 are accessible for loading. Crank handle 47 will be turned until all of the members 38 have been brought in front of the opening closed by doors 18 and all have been loaded with butter. The butter will be kept firm and hard by the low temperature maintained in casing 10 by the ice or other refrigerant 98. It will be noted that members 38 pass close to the wall 21b of casing 21 so that they will be efficiently cooled. When handle 47 is to be turned for rotating member 34 and members 38, the operator will pull outwardly upon the knob or handle 44 which will move pin 40 outwardly against the resistance of spring 43 and remove said pin from the opening in its member 39. When the members 38 are disposed, as shown in Fig. 2, pin 40 will be urged into the opening in member 39 which is at the side of the device so that member 34 will be held from further rotation. The device is now ready to cut and dispense the butter. The operator will depress or turn handle 78, as indicated in Fig. 1. When this is done shaft 64 is turned and frame 70 is swung downwardly so that wire 71 moves across the front of the member 38 in the bottom position. The butter, which has been fed to the position shown in Fig. 3, will then have a slice or pat cut from its front end and this slice will drop into member 84. Member 86 will be moved to uncover the opening in the bottom of member 84 so that the pat of butter 91 will drop down and may be received in a dish or tray 92 placed on the table or other support on which the device rests. When frame 70 moves downwardly sufficiently so that the left-hand end of slot 70c, as seen in Fig. 2, engages pin 12, arm 63 will be moved in a counter-clockwise direction and pawl 62 will be moved backwardly to engage the next tooth on ratchet wheel 61. Pawl 62 is maintained in engagement with ratchet wheel 61 by the spring 49. Rearward movement of arm 63 will be limited by the screw 74. When frame 70 swings upwardly either

under the influence of spring 82 or by the operator moving handle 78 back to the full line position shown in Fig. 1, said frame will come into position above the lower member 38. When the wire 71 has cleared member 38, the end of slot 70c will again engage pin 12 and move arm 63 in a clockwise direction, thus causing pawl 62 to move ratchet wheel 61 the distance of one tooth. This will rotate gears 8 and 57 and turn sprocket 53 to move the upper run of chain 54 to the right, as shown in Fig. 3. The member 55 engaging the block of butter 93, as shown in Fig. 3, will now move said block forwardly the desired distance so that it will project beyond the end of its member 38, as shown in Fig. 3. The upward movement of frame 70 and the clockwise movement of arm 63 can be determined by the position of the stop screw 76. It will be seen that chain 54 is movable only in one direction which causes the sprockets 54 and 52 and the members 55 to move in a clockwise direction, as shown in Fig. 3. It will also be seen that members 55 extend through the opening 38a in the side of each member 38, as shown in Fig. 5, and that these members 55 can enter the rear ends of members 38, move therethrough and pass out at the front ends thereof. When the machine is first operated, the crank handle 78 may have to be moved several times to get the block of butter 93 into position to be cut. As shown in Fig. 4, the members 38 are long enough to accommodate two standard quarter pound blocks of butter. The peripheral flange 34c on rear member 34 forms a stop for the blocks of butter 93 when they are loaded into members 38. When ice is used for the refrigerant the water formed by melting of the same will drain through openings 21d and drop into receptacle 25. This can be removed and emptied as necessary by removing door 13 by means of its handle 14.

From the above description it will be seen that I have provided a compact, efficient and very convenient device for cutting and dispensing pats of butter. The device can be easily and rapidly operated and it is of a convenient size for use in restaurants, hotels and other places where the pats of butter are used. The structure is fairly simple and there are no parts which will require any appreciable attention for maintenance. The device will be nicely painted or coated on the exterior so that it will have a very pleasing appearance. It will be apparent that the device will have a high degree of utility for the purpose intended.

It will of course be understood that various changes may be made in the form, details, arrangement and proportions of the parts, without departing from the scope of applicant's invention, which generally stated, consists in an apparatus capable of carrying out the objects above set forth, in the parts and combinations of parts disclosed and defined in the appended claims.

What is claimed is:

1. A butter-dispensing machine having in combination, an outer casing having an insulated wall, an inner casing within said casing forming a chamber with the wall thereof, said inner casing having a semi-cylindrical upper end, a bottom for said chamber sloping toward one side of said outer casing, said chamber having a drain opening at said side, a receptacle carried in said outer casing below said drain opening, said outer casing having a door through which said receptacle can be removed, and a rotatable member having radially disposed and circumferentially spaced elongated chambers each substantially rectangular

lar in cross section and adapted to receive an elongated block of butter, said chambers being movable closely adjacent said semi-cylindrical portion of said inner casing to be cooled thereby.

2. A butter-dispensing machine having in combination, a member rotatable about a central longitudinal axis, a plurality of chambers carried by said member arranged in radially disposed and circumferentially spaced position, each of said chambers being open at one side and adapted to receive and guide an elongated block of butter, a pair of sprockets, an endless chain running over said sprockets and having a side extending substantially parallel to said chambers, said chambers being successively positioned adjacent said side of said chain by rotation of said first mentioned member, butter-propelling members carried by said chain adapted to extend through the open side of the chamber adjacent said chain, enter one end thereof and pass out at the other end thereof, said chain being movable only in one direction, a substantially three-sided swinging frame having an open side, a rectilinear wire secured at its ends in said frame and movable across the end of said chamber adjacent said chain, a handle, and means actuated by movement of said handle for swinging said frame to cut a slice of butter and means for then moving said frame upwardly and moving said chain and butter-propelling members a distance equal to the thickness of said slice.

3. A butter-dispensing machine having in combination, a member rotatable about a central longitudinal axis, a plurality of chambers carried by said member arranged in radially disposed and circumferentially spaced position, each of said chambers being open at one side and adapted to receive and guide an elongated block of butter, a pair of sprockets, an endless chain running over said sprockets and having a side extending substantially parallel to said chambers, said chambers being successively positioned adjacent said side of said chain by rotation of said first mentioned member, butter-propelling plates carried by said chain adapted to extend through the open side of the chamber adjacent said chain, enter one end thereof and pass out at the other end thereof, said chain being movable only in one direction, a swinging frame, a shaft at one side of said first mentioned member on which said frame is pivoted, a rectilinear wire carried by said frame and movable across the end of the chamber adjacent said chain, a spring acting to move said frame to its upper position, a handle, and means actuated by movement of said handle for swinging said frame downwardly to cause said wire to cut a slice of butter from the block of butter in said chamber adjacent said chain, the said frame being movable upwardly by said spring or by the operator moving said handle, and means actuated in the upper movement of said frame for moving said chain a distance equal to the thickness of said slice.

4. A butter-dispensing machine having in combination, a member rotatable about a central longitudinal axis, a plurality of chambers carried by said member arranged in radially disposed and circumferentially spaced position, each of said chambers being open at one side and adapted to receive and guide an elongated block of butter, a pair of sprockets, an endless chain running over said sprockets and having a side extending substantially parallel to said chambers, said chambers being successively positioned adjacent said side of said chain by rotation of said first men-

tioned member, butter-propelling members carried by said chain adapted to extend through the open side of the chamber adjacent said chain, enter one end thereof and pass out at the other end thereof, said chain being movable only in one direction, a swinging frame, a shaft at one side of said first mentioned member on which said frame is pivoted, a rectilinear wire carried by said frame and movable across the end of the chamber adjacent said chain, an arm secured to said shaft, said frame having a portion adjacent said arm with an arcuate slot therein concentric with the axis of said shaft, a pin secured in said first mentioned arm and extending into said slot, a ratchet wheel connected to one of said sprockets for intermittently moving the same, a pawl connected to said first mentioned arm and engaging said ratchet wheel, a handle connected to said shaft whereby the downward movement of said handle will swing said frame to cause said wire to cut a slice of butter from said block in said chamber adjacent said chain and after said frame has swung upwardly above said chamber said pin will be engaged by one end of said slot and swing said first mentioned arm and pawl to move said chain a distance equal to the thickness of said slice.

5. The structure set forth in claim 4, and a spring connected to said frame for swinging the same upwardly and actuating said arm.

6. The structure set forth in claim 4, and adjustable stops for determining the upper and lower positions of said frame.

7. A butter-dispensing machine having in combination, a member rotatable about a central longitudinal axis, a plurality of chambers carried by said member arranged in radially disposed and circumferentially spaced position, each of said chambers being open at one side and adapted to receive and guide an elongated block of butter, a pair of sprockets, an endless chain running over said sprockets and having a side extending substantially parallel to said chambers, said chambers being successively positioned adjacent said side of said chain by rotation of said first mentioned member, butter-propelling plates carried by said chain adapted to extend through the open side of the chamber adjacent said chain, enter one end thereof and pass out at the other end thereof, said chain being movable only in one direction, a swinging frame, a shaft at one side of said first mentioned member on which said frame is pivoted, a rectilinear wire carried by said frame and movable across the end of the chamber adjacent said chain, a handle for oscillating said shaft to move said frame and cause said wire to cut a slice of butter, and means operated by movement of said frame to move said chain and butter-propelling plates a distance equal to the thickness of said slice.

8. The structure set forth in claim 7, and a handle adjacent said handle for rotating said first mentioned member.

9. A butter-dispensing machine having in combination, a casing having a front wall and a top wall, a member disposed in said casing and rotatable about a central longitudinal axis, a plurality of chambers carried by said member and arranged in radially disposed and circumferentially spaced relation, said chambers being substantially rectangular in cross section, and arranged to receive and guide elongated blocks of butter, said chambers being open and unobstructed at one end, said casing having an opening in said front wall spaced from said top wall adja-

cent the ends of said chambers and a movable closure for said opening secured to said casing, said opening exposing the ends of a plurality of said chambers whereby a plurality of said chambers may be loaded by placing said blocks therein by a movement alined longitudinally with said chambers.

10. The structure set forth in claim 9, said member having an octagonal periphery to which said chambers are secured, said opening exposing three of said chambers.

11. A butter-dispensing machine having in combination, a member rotatable about a central longitudinal axis, a plurality of chambers carried by said member arranged in radially disposed and circumferentially spaced position, each of said chambers being open at one side and adapted to receive and guide an elongated block of butter, a pair of sprockets, an endless chain running over said sprockets and having a side extending substantially parallel to said chambers, said chambers being successively positioned adjacent said side of said chain by rotation of said first mentioned member, butter-propelling members carried by said chain adapted to extend through the open side of the chamber adjacent said chain and move butter therein, a swinging frame, a shaft at one side of said first mentioned member on which said frame is pivoted, a rectilinear wire carried by said frame and movable across the end of the chamber adjacent said chain, a spring acting to move said frame to its upper position, a handle, and means actuated by movement of said handle for swinging said frame downwardly to cause said wire to cut a slice of butter from the block of butter in said chamber adjacent said chain, the said frame being movable upwardly by said spring or by the operator moving said handle, and means actuated in the upper movement of said frame for moving said chain a distance equal to the thickness of said slice.

12. A butter-dispensing machine having in combination, a member rotatable about a central longitudinal axis, a plurality of chambers carried by said member arranged in radially disposed and

5 circumferentially spaced position, each of said chambers being open at one side and adapted to receive and guide an elongated block of butter, a pair of sprockets, an endless chain running over said sprockets and having a side extending substantially parallel to said chambers, said chambers being successively positioned adjacent said side of said chain by rotation of said first mentioned member, butter-propelling members carried by said chain adapted to extend through the open side of the chamber adjacent said chain for moving butter therethrough, a shaft at one side of said first mentioned member on which said frame is pivoted, a rectilinear wire carried by 10 said frame and movable across the end of the chamber adjacent said chain, an arm secured to said shaft, said frame having a portion adjacent said arm with an arcuate slot therein concentric with the axis of said shaft, a pin secured in said first mentioned arm and extending into said slot, a ratchet wheel connected to one of said sprockets for intermittently moving the same, a pawl connected to said first mentioned arm and engaging said ratchet wheel, a handle connected to said shaft whereby the downward movement of said handle will swing said frame to cause said wire to cut a slice of butter from said block in said chamber adjacent said chain and after said frame has swung upwardly above said chamber said pin will be engaged by one end of said slot and swing said first mentioned arm and pawl to move said chain a distance equal to the thickness of said slice.

LEONARD HERBER.
